2109486 9/1972 Germany .

Primary Examiner—Louis S. Zarfas*Assistant Examiner*—Greg Andoll*Attorney, Agent, or Firm*—Price, Heneveld, Cooper, DeWitt and Litton**[57] CLAIM**

The ornamental design for the combined bowling ball rack and table with seating, as shown and described.

DESCRIPTION

FIG. 1 is a front perspective view of a bowling center modular wall showing our new design;

FIG. 2 is a top plan view thereof;

FIG. 3 is a rear elevation view thereof;

FIG. 4 is a front elevation view thereof; and,

FIG. 5 is a left end elevation view thereof.

The bottom of the combined bowling ball rack and table with seating is plain and unornamented and forms no part of the claimed design.
